UNITED STATES PATENT OFFICE.

JOHN P. THOMPSON, OF FALL RIVER, ASSIGNOR OF ONE-HALF TO THE WHITIN MACHINE WORKS, OF WHITINSVILLE, MASSACHUSETTS.

MACHINE FOR AND METHOD OF CARDING WOOL, &c.

SPECIFICATION forming part of Letters Patent No. 443,416, dated December 23, 1890.

Application filed November 8, 1887. Serial No. 264,620. (No model.)

To all whom it may concern:

Be it known that I, JOHN P. THOMPSON, of Fall River, in the county of Bristol and State of Massachusetts, have invented certain new and useful Improvements in Machines for and Methods of Carding Wool, &c., of which the following is a full, clear, and exact description, reference being had to the accompanying drawings, forming a part of this specification.

This invention relates to a method of and a machine for carding cotton, wool, or other fibrous material.

The objects of my invention are to render the carding-machine more efficient and to improve the quality of the carded lap or sheet produced from the machine.

To the aforesaid purposes my invention, briefly stated, consists, essentially, in introducing into the carding-machine pressing or packing mechanism for pressing and packing the loosened fiber into a smooth sheet or lap, and, further, the invention consists in the step of packing the fiber in the operation of carding.

In order that my invention may be fully understood, I have illustrated in the accompanying drawings and will proceed to describe the best form thereof so far devised by me, with the knowledge that the same may be variously modified, without, however, making a substantial departure from the spirit of my invention.

In the accompanying drawings, Figure 1 is a side view of a portion of a carding machine or attachment embodying my improved packing mechanism, and Fig. 2 is an enlarged detached view of the packer with the rock-shaft shown in section.

In the said drawings, like numbers of reference designate corresponding parts throughout.

Referring to the drawings 3, designates the machine-framing, 4 the carrier-cylinder, and 5 the co-operating doffer-roll, from which the fiber is doffed by means of the vibrating doffer or comb 6, which is fast upon the rock-shaft 7, operated by means of the arms 9 and 10, shaft 11, pulley 12, band 13, band-wheel 14, and the shaft 15. The rotary feed-rolls 16 receive the lap or sheet coming from the

doffer and the packer, which will now be described, and may feed the same to a main cylinder. (Not shown.)

The vibrating packer 17 consists in a loose sleeve 18, having the internal raised bearing-ridges 19 for decreasing the friction of the sleeve upon the incased rock-shaft 7, and from the sleeve 18 extend the arms 20, which are adapted to carry the presser-plates 21, having the packing fingers or teeth 22 for manipulating the doffed fleece as it passes thereunder from the doffer to the feed-rolls 16. The packer is vibrated by means of the rigid bar 23, extending from the sleeve 18, and provided with slot 24, through which extends the stud 25 on the upper end of the connecting-rod 26, connected eccentrically with the disk 27, receiving its motion from shaft 28, which may be driven from the shaft 15 or any other convenient rotating shaft. The packing-bed 29 extends underneath the packer 17 from the doffer to the feed-rolls.

It will now be obvious that, as the fleecy fiber is delivered from the doffer 6 and comes under the action of the vibrating packer 17 the loosened fiber will be worked into a smooth and somewhat compact sheet or lap by virtue of the blows of the packer, and the same will be introduced to the feed-rolls in this packed or pressed condition, and thence to the main cylinder, which is not shown.

By virtue of my improvements I greatly improve the efficiency of the carding-machine and produce a superior quality of lap.

Having thus described my invention, I claim as new and desire to secure by Letters Patent—

1. The combination, as hereinbefore set forth, with the doffer-roll, of the doffer for doffing the fiber from the said roll, and a vibrating packer constructed to press the doffed fiber into a smooth sheet or lap, the bed 29, and feed-rolls 16, substantially as and for the purpose herein described.

2. The combination, as hereinbefore set forth, with the carrier-cylinder and the doffer-roll co-operating therewith and the feed-rolls, of the doffer for the said roll, and the vibrating packer constructed to press and pack the fiber doffed from said roll, and the

packer-bed 29, substantially as and for the purpose herein described.

3. The combination, as hereinbefore set forth, with the shaft and the packer having a sleeve loosely mounted on the shaft and provided with a slotted arm, of a rotary disk and a connecting-rod connecting the disk and the slotted arm for vibrating the packer, substantially as described.

10 4. The method herein described of carding fibrous material, the same consisting in col-

lecting the partially carded and cleaned fiber after it has passed the licker-in of the carding-machine, packing and compressing the fiber so collected into a sheet or lap, and then feeding the lap so packed and compressed to the main carding-cylinder, as described.

JOHN P. THOMPSON.
